Primary Examiner — Sheryl Lane(74) *Attorney, Agent, or Firm* — Ryan, Kromholz & Manion, S.C.(57) **CLAIM**

The ornamental design for an offset cable tie, as shown and described.

DESCRIPTION

FIG. 1 is a perspective view of a first embodiment of the offset cable tie;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front end elevation view thereof;

FIG. 7 is a back end elevation view thereof;

FIG. 8 is a perspective view of a second embodiment of the offset cable tie;

FIG. 9 is a right side elevation thereof;

FIG. 10 is a left side elevation thereof;

FIG. 11 is a top plan view thereof;

FIG. 12 is a bottom plan view thereof;

FIG. 13 is a front end elevation view thereof; and,

FIG. 14 is a back end elevation view thereof.

The broken lines in FIGS. 1-14 represent portions of the article and form no part of the claimed design.

FIGS. 1-5 and 8-12 show a break in the cable tie. The appearance of any portion of the article between the break lines forms no part of the claimed design.
